(57) **CLAIM**

The ornamental design for a tool for engaging and disengaging connectors, as shown and described.

DESCRIPTION

FIG. 1 is a front isometric view of a tool for engaging and disengaging connectors;

FIG. 2 is a right view thereof;

FIG. 3 is a left view thereof;

FIG. 4 is a bottom view thereof;

FIG. 5 is a top view thereof;

FIG. 6 is a front view thereof; and,

FIG. 7 is a back view thereof.

1 Claim, 4 Drawing Sheets
